UNITED STATES PATENT OFFICE.

CHARLES A. COOLEY, OF MONTREAL, QUEBEC, CANADA.

MACHINE FOR COVERING WIRE.

SPECIFICATION forming part of Letters Patent No. 416,254, dated December 3, 1889.

Application filed October 24, 1888. Serial No. 289,006. (No model.)

To all whom it may concern:

Be it known that I, CHARLES A. COOLEY, a citizen of the United States, residing in Montreal, in the Province of Quebec, Canada, have 5 invented certain new and useful Improvements in Machines for Covering Wire, of which the following is a specification.

My invention relates to wire-insulating machines of that particular class in which the wire is fed through the hollow spindles upon which the bobbins containing the insulating thread or yarn are mounted, and which are adapted for winding or filling the bobbin with the insulating-yarn, and also for winding said 15 yarn upon the wire, without removing the bobbins from the machine or from the position in which they are wound.

The invention embraces electrical apparatus for stopping the machine whenever the 20 yarn breaks either in the insulating operation or in the bobbin-winding operation.

The broad idea of stopping a winding-machine when the thread breaks I do not claim as my invention; but the particular manner 25 of carrying out such feature will be embraced in claims hereto appended.

Referring to the accompanying drawings, Figure 1 represents a front elevation of the machine adapted to run two bobbins simultaneously. In this view the upper portion of the machine is shown as filling a bobbin, while the lower part is shown as winding the yarn upon the wire. It will be understood, however, that these two operations will not 35 be carried on simultaneously, but that either one of them may be accomplished on both parts of the machine simultaneously. Fig. 2 represents a detail view of a part of the apparatus shown in Fig. 1; and Fig. 3 represents a side or end elevation of the apparatus, the winding-spindles being removed, the object of this being simply to show the thread-guiding mechanism for winding the bobbins and the apparatus for operating the clutch, 40 the clutch being shown disengaged. Fig. 4 represents a detail of the circuit-closing mechanism operated upon the breaking of a thread.

For the sake of convenience of illustration, the magnet controlling the clutch is shown in Fig. 3 reversed in position relatively to the machine.

Motion is imparted to the machine from a horizontal shaft A by means of belt a, which makes a quarter-turn over guide-pulleys a' and thence around the loose portion or member B' of a friction-clutch B. This clutch controls the main shaft C of the machine and may be operated either automatically by 55 electricity or by hand. A lever b, having a handle at its outer end, is pivoted to the frame at b' and to a sleeve around the lower end of the shaft, said sleeve bearing freely against the loose portion of the clutch. The lever has a shoulder b², which, when the machine is running, rests upon the upper end 60 of a pivoted arm b³, thus holding the loose member up in contact with the tight member B².

The machine is adapted to run at a high rate of speed, and its momentum is sufficient 70 to keep it in motion some time after the clutch becomes disengaged. I have therefore provided an automatic brake mechanism consisting of the weighted disk b⁶, located loosely on the shaft above the light clutch and 75 adapted to slide thereon. This disk is surrounded by a strap-lever b⁵, which is connected with it at the points b⁷. The strap-lever is pivoted at b⁸ to the frame and is pivotally connected with link b⁴, which latter is 80 hinged to lever b. When the clutch is engaged, the disk is held out of contact with the tight part of the clutch; but when it becomes disengaged by the lever b dropping the disk falls upon the tight portion of the clutch and 85 retards its movement. While this brake is ordinarily automatic in its operation, by manipulating the lever b by hand the motion of the machine may be bridled to any degree.

The winding mechanism is mounted in a 90 suitable frame D, having in the instance shown three platforms K K K for supporting the different parts of the apparatus. The upper platform simply supports a drum or wire-feeding pulley K', while the two platforms below support mechanisms which are nearly identical with each other. It will therefore only be necessary to describe in detail one of the mechanisms. The shaft C extends to the full length of the machine and is provided 95 with pinions c, which drive, through intermediate gearing, the tubular bobbin-shafts, which

have their bearing in the brackets C^2 . The intermediate gearing in one case preferably embraces one more pinion than in the other, so that the spindles will be turned in opposite directions. The bobbins H' are mounted loosely upon their shafts and rest normally upon the journal-boxes formed in the brackets C^2 .

I will first describe the mechanism for or manner of filling the bobbins. This mechanism is shown in the upper part of the machine. A vertically-reciprocating rod E is moved by the cam-wheel E' . (Shown best in Fig. 3.) This is a heart-shaped cam, upon the periphery of which rests the lever e , which is connected with the rod E . The rotation of the cam causes the reciprocation of the rod. Motion is imparted to this cam through a worm R and gear from the main shaft C . To the rod E is adjustably attached by means of a friction-tight hub a lateral arm f , carrying a guide or frame f' at its inner end, which stands quite close to the bobbin. This frame is provided with weights f^2 , having hooks which pass over the strands which lead from the supplying-bobbins M to the spindle. The hooks suspend the weights, and when a thread breaks said weights or weight is allowed to drop, closing an electric circuit by falling upon two terminals fixed in the arm supporting the weights, as will be readily seen in Fig. 2. The reciprocating movement of the rod E carries the strands up and down in front of the bobbins, thus forming an even winding. When a bobbin is being wound, the intermediate gearing between shaft C and the spindle is broken by the removal of one of the pinions, and the bobbin is then revolved through a small belt g , which passes over grooved pulleys $c' c'$ on the end of the bobbin and upon shaft C .

It should be stated that the bobbins are loose upon their bearings, so that the belt g may turn them for filling purposes, and also in order that they may slowly revolve in the operation of winding the yarn upon the wire.

Returning to the manner of closing the electric circuit when one of the weights falls, it will be seen that the circuit leads from battery O' through magnet O , thence to contacts $i i'$, and back to battery. A branch circuit runs to the contacts adjacent to the suspended weights. The armature of this magnet is connected with the pivoted lever b^3 , which supports the clutch-lever b . When a weight f^2 drops and closes the circuit, the armature is attracted and the support of the arm b is removed, thus allowing the loose clutch to drop out of contact with the tight clutch and stopping the machine. The electric circuit just described also includes a pair of contacts $o o'$, one of which is stationary and the other connected with the lever b . When this lever drops, the circuit through the magnet is immediately broken by the parting of these contacts, thus preventing

waste of battery. When the bobbins have been wound, the arm f , with its attachments, is removed or drawn back and the machine threaded for winding upon the wire.

Referring now to the mechanism in the lower part of the machine, it will be seen that the yarn h passes through an eye in one of the fliers H , thence over a pivoted spring-hook h' , thence through a guide-eye h^2 , and finally to the winding-head h^3 . This head and the fliers are of the usual construction and need not be described in detail herein. To start the winding operation now, the displaced pinion which was removed for the purpose of filling the bobbin is replaced and belt g removed. The clutch then being thrown in, the gearing turns the spindle, and the fliers carry the thread around, winding it on the wire in opposite directions.

When for any reason the thread breaks, the pivoted spring-arm h' is thrown outward by centrifugal force and strikes the pivoted circuit-closing arm i , which drops upon the corresponding contact i' and closes the electric circuit through the magnet, thus operating the clutch and stopping the machine. This construction is best shown in Fig. 4.

The wire, after passing from its reel over guide-pulley N , passes up through tension device n , thence through the two spools, and twice around the feed-drum K' . This drum is turned at a regular speed by means of gearing operated from the worm R upon shaft C . The said worm rotates a pinion on the shaft-carrying cam E . This pinion in turn drives, through intermediate gears and shaft, a pinion which meshes with a gear fixed to the drum-shaft, as shown.

Having described my invention, I claim—

1. In a winding-machine, a reciprocating rod carrying thread-guides and electric contacts, in combination with a rocking lever and a cam for reciprocating said rod, thread-guides, and contacts, whereby the relative positions of the guides and contacts is constantly the same.

2. In a winding-machine, the main shaft and clutch controlling the same, a rotating spindle geared to the shaft, the flier H , moving with said spindles, and the pivoted arm h' , connected with said flier and normally retained by the thread, in combination with an electric circuit and a circuit-closer operated by the pivoted arm h' upon the breaking of a thread, a magnet included in said circuit, and levers between the armature of the magnet and said clutch, which are moved to open the clutch when the magnet is energized.

3. A main shaft adapted to drive through gearing the spindles and wire-feeding drum, in combination with said gearing, spindles, and drum, a clutch upon the main shaft, a magnet, an armature connected with the pivoted latch-bar, a lever connected with the loose portion of the clutch held in position

by said latch-bar, and an electric circuit including contact-points and the said magnet, and a weight held in suspension by the thread, the said circuit being closed by the fallen weight upon the breaking of a thread, as set forth.

In witness whereof I have hereunto signed

my name in the presence of two subscribing witnesses.

CHARLES A. COOLEY.
